UNITED STATES PATENT OFFICE.

PETER A. SCHAEFER, OF GREENSBURG, PENNSYLVANIA.

SPARK-INTENSIFIER.

1,395,737.

Specification of Letters Patent.

Patented Nov. 1, 1921.

Application filed August 24, 1920. Serial No. 405,580.

To all whom it may concern:

Be it known that I, PETER A. SCHAEFER, citizen of the United States, residing at Greensburg, in the county of Westmoreland 5 and State of Pennsylvania, have invented certain new and useful Improvements in Spark-Intensifiers, of which the following is a specification.

This invention relates to an improved 10 spark intensifier for internal combustion engines and has as one of its principal objects to provide a simple and practical device which may be readily interposed in the circuit of a spark plug for intensifying the 15 spark given off at the plug.

The invention has as a further object to provide a device employing a plurality of spark gaps across which the current must flow to the plug for thus insuring the generation of a good hot spark at the plug.

And the invention has as a still further object to provide a device wherein the spark gaps thereof will be inclosed so that, in practical use, the device will be entirely safe and 25 wherein the occurrence of a spark at any one of said gaps may be readily observed.

Other and incidental objects will appear hereinafter.

In the drawings:

30 Figure 1 is a sectional view showing my improved device connected to a spark plug, the plug being conventionally illustrated, and

35 Fig. 2 is a perspective view showing the device in detail.

Referring now more particularly to the drawing, I employ a stop or core 10 of suitable insulating material. Riveted or otherwise secured to the end portions of the core 40 are terminals which, for convenience, have been indicated at 11 and 12 respectively. As will be observed, these terminals are offset to extend axially of the core and at their outer end portions are provided with suitable 45 openings therethrough. Engaged through the core between the inner ends of the terminals 11 and 12 is a series of spaced headed electrodes 13. Three of said electrodes are preferably employed and, as will 50 be noted, the heads of said electrodes are arranged at the upper side of the core, the distance between the heads as well as the distance between the heads of the outermost electrodes and the inner ends of the 55 terminals being equal to provide a plurality of spark gaps. Fitted over the terminals

11 and 12 are metallic thimbles 14, the end walls of which are slotted to receive the terminals therethrough so that said walls abut the offsets in the terminals and preferably the end walls of the thimbles are soldered or otherwise fixed to the terminals for holding the thimbles rigid thereon. Fitted at its end portions into the thimbles and centered thereby with respect to the core, is a 60 transparent housing tube 15. This housing tube may be of glass or other approved transparent material and surrounding each of the end portions of the tube within the thimbles is a cement or other approved 65 binder 16 firmly uniting the tube with the thimbles. Thus, as will be seen, the tube will coöperate with the thimbles to provide a sealed housing for the spark gaps, the joints between the tube and the thimbles as well as 70 the joints between the thimbles and the terminals 11 and 12 being closed. Consequently, in the practical use of the device, a spark occurring within the housing cannot 75 ignite fuel vapors collected about the device 80 so that the device will, accordingly, be entirely safe. Fitted through the terminal 12 is a binding post 17 which carries a thumb nut 18.

In Fig. 1 of the drawing, is shown the 85 manner in which my improved intensifier is used. As illustrated, the terminal 11 of the device is connected to a spark plug which, for convenience, has been conventionally shown at 19, while the circuit wire 20 90 ordinarily connected directly to the plug is engaged with the binding post 17, being secured upon said post by the nut 18. Thus, current flowing through the wire 20 must pass through the device to the plug. Upon 95 reaching the inner end of the terminal 12 the current will first jump to the adjacent one of the electrodes 13, then to the intermediate electrode, then to the third electrode, and finally to the terminal 11, crossing all 100 of the spark gaps. As will be seen, this will result in the creation of a strong hot spark between the electrodes of the plug. The device will, therefore, operate to insure dependable firing of the plug and due to the 105 intensity of the spark created at the plug will tend to maintain the electrodes thereof clean and free of oil or carbon.

Having thus described the invention, what is claimed as new is:

1. A device of the character described including an insulating core, terminals se-

cured to one side of the core and offset to extend axially thereof, an electrode mounted upon the core to provide spark gaps between the electrode and said terminals, 5 thimbles fitting over the terminals to abut the offsets therein, and a housing tube extending between and supported by the thimbles to inclose said spark gaps.

2. An intensifier including an insulating 10 strip, terminals carried by the end portions of the strip, means extending through the strip and said terminals securing the terminals to the strip, an electrode upon the strip between the inner ends of said terminals

providing spark gaps between the electrode and the terminals, and a housing inclosing said spark gaps. 15

3. An intensifier including spaced terminals, an insulating strip forming a rigid connection between said terminals, an electrode upon the strip between the terminals providing spark gaps between the electrode and the terminals, thimbles upon the terminals, and a tube extending between said thimbles housing the strip. 20

25. In testimony whereof I affix my signature.

PETER A. SCHAEFER. [L.S.]
